UNITED STATES PATENT OFFICE.

WILLIAM L. HORNE, OF MERIDEN, ASSIGNOR TO THE HORNE VACUUM COMPANY, OF HARTFORD, CONNECTICUT.

ELECTRIC-LIGHTING SYSTEM.

SPECIFICATION forming part of Letters Patent No. 400,214, dated March 26, 1889.

Application filed October 28, 1887. Serial No. 253,639. (No model.)

To all whom it may concern:

Be it known that I, WILLIAM L. HORNE, a citizen of the United States, residing at Meriden, in the county of New Haven and State 5 of Connecticut, have invented certain new and useful Improvements in Electric-Lighting Systems; and I do hereby declare the following to be a full, clear, and exact description of the invention, such as will enable others 10 skilled in the art to which it appertains to make and use the same.

My present invention relates to the art of electric lighting, and more particularly to electric lighting by means of what are known 15 as "arc" lamps.

It consists in certain means for accomplishing desirable results, and especially in means whereby the life of the carbons is indefinitely prolonged and a greater amount of illuminating-power is secured for the expenditure of 20 the same amount of electrical energy.

In the accompanying drawings I have shown one mode in which I have contemplated employing my invention, and have 25 fully disclosed said invention in the following description and claims.

In the drawings, Figure 1 is a perspective view of a lamp and its inclosing-case. Fig. 2 is a section of the bottom plate of the lamp- 30 case. Fig. 3 is a view of a portion of a system or plant arranged in accordance with my invention. Fig. 4 is a diagram of a single plant of three lamps.

It is well known that the carbons of arc 35 lamps are rapidly decomposed when burning in the open air, necessitating the supply of each lamp with fresh carbons at short intervals. This is a great expense to the companies furnishing the light, not only for the 40 carbons themselves, but also for the wages of the men required to effect the change. The constant dropping of heated particles from the decomposing carbons is also a frequent 45 source of accidents by fire, and precludes the use of this means for lighting in places where the light would otherwise be desirable. I avoid these objectionable results by placing the lamp in a glass case and forming therein a total or partial vacuum, as may be found 50 most efficient. As the electric current will

pass more readily from one carbon to another in vacuum than in open air, I am enabled by this means to elongate the arc and thereby increase the illuminating-power of the lamp.

In the construction shown in the drawings 55 the lamp is provided with an inclosing-case consisting of an inclosing-cylinder of glass, A, fitted at top and bottom into metallic caps a a'. The cylinder is connected to the caps by an air-tight joint, and the caps are provided with 60 suitable means whereby the carbons can be inserted or removed when desired.

In Fig. 2 I have shown the cap a' provided with a screw-plug, a², which serves as a holder for the lower carbon; but the lower carbon 65 may be held by a part of the lamp, as usual. The cap a may be provided with a similar plug fitting an aperture therein sufficiently large and so located as to permit the insertion and removal of the upper carbons. The feeding 70 mechanism is located in the case and the electrical connections may be made through the plugs or through the caps or through the upper cap alone, as may be preferred. In some cases I may make the casing inclosing the regulat- 75 ing mechanism of the lamp air-tight and make the same the top cap of the inclosing-case. I have also contemplated forming a case by dispensing with the lower cap and making the bottom of the case entirely of glass, and pref- 80 erably integral with the cylindrical portion. A source of obstruction to the rays of light beneath the lamp is thereby avoided.

I prefer to exhaust the air from the lamp-case 85 by means of an air-exhausting device located at the central station of a plant and connected to the lamps by means of a system of pipes similar to that used in gas-lighting, but smaller. These pipes may be placed in the ground or carried on the poles erected for 90 the light-conductors. In Fig. 3 I have shown part of such a system in which the air-exhaust pipes are located partly underground and partly upon the conductor-supports; and in Fig. 4 I have shown in a diagrammatic way a 95 complete plant of three lamps. In these figures, S is the central station, s the electric generator, and s' the exhausting device located at the central station. A' A' A' are the lamps; b b, the electric conductors; C, the main air- 100

exhausting pipe, and *ccc* the pipes connecting the lamp-cases with the pipe C. Each of the pipes *ccc* is provided with a cut-off cock near the lamp. In each of the lamp-cases I employ a valve, *e*, of peculiar construction. This valve is suspended above the open end of pipe *c* by a sensitive spring. This spring is of such strength as to just maintain the valve in the position shown and permit the air to be exhausted slowly and gradually from the lamp-case; but on the sudden influx of air to the lamp, caused by breaking the case or other accident, the spring will immediately yield and cause the valve to close pipe *c*.

15 In my system the feeding mechanism is constructed to maintain an arc of a length corresponding to the degree of exhaustion within the case. The carbons will be decomposed very slowly and will last a long time without change. When it becomes necessary to replace the carbons in a lamp, the cock near the lamp is turned so as to cut off communication with the main air-exhaust pipe. The carbons are then changed, the lamp sealed, and 20 the cock opened. This adds to the pipe system of circulation only the air in the lamps in which the carbons are changed. A sufficient time before the hour for lighting the lamps the air-exhausting mechanism is put in 25 operation and the air withdrawn from the various main pipes and lamp-cases until the desired degree of rarefaction is obtained. The lamps are then lighted and the exhaust continued at such speed and to such extent as to 30 maintain the proper degree of exhaust and

removing all air entering the system by reason of leakage, and all gases generated in the lamps. I may prefer to employ two exhaust mechanisms of different capacities—the larger to be employed in exhausting the air in the 40 first instance and the smaller to be used where it is only desired to maintain the degree of exhaustion attained and remove the gas.

I do not desire to be limited to my exact 45 constructions, as they may be greatly varied without departing from the spirit of my invention.

What I claim, and desire to secure by Letters Patent, is—

1. A case for inclosing an arc lamp, provided with an aperture at the top for the removal of the upper carbon, a closure for the same, and aperture, at the bottom for the removal of the lower carbon, and a closing-plug 55 for said aperture, provided with a socket for receiving and holding the lower carbon in proper position, substantially as described.

2. An air-tight inclosing-case for an arc lamp, an exhaust-pipe opening into and communicating with said case, and a valve above the opening within the case, substantially as described.

In testimony whereof I affix my signature in presence of two witnesses.

WM. L. HORNE.
